CLIP RING DISPENSERS

Chester P. Coldren, Canton, Ohio, assignor to Eaton Manufacturing Company, Cleveland, Ohio, a corporation of Ohio

Filed Jan. 29, 1960, Ser. No. 5,384
8 Claims. (Cl. 211—59)

Broadly, this invention relates to a clip ring dispenser and application but more specifically, provides for a dispenser of a unique and novel assembly functioning to orientate and maintain a stack of rings in proper alignment for dispensing by a suitable applicator.

Clip ring dispensers of known design are generally provided with an assembly operable to receive a plurality of rings disposed on a carrier in the form of a rod or tubular member. Depending upon the structural configuration of the ring, the carrier is designed to accommodate the rings such that each ring is identically arranged thereon in proper alignment for positioning on the dispenser. In general, the function of the dispenser is to transfer the oriented rings from the carrier portion to a position from which they can be handled by the applicator, maintaining throughout the transferring operation, the desirable and necessary constant ring alignment provided by the carrier.

Therefore, it is a principal object of this invention to provide a ring dispenser operable to maintain constant ring alignment during the dispensing operation.

Another object of this invention is to provide a ring dispenser comprised of relatively few parts wherein only a minimum number of these parts need be changed to accommodate various ring sizes.

It is still another object of this invention to provide a ring dispenser which is basically of a construction facilitating ease of assembly and requiring little maintenance during the operation thereof.

A further object of this invention is to provide a novel dispenser which is simple in structure resulting in economical costs for its production.

Further objects and advantages of the invention will be apparent from the following description taken in connection with the drawings forming a part of the specification and in which:

FIGURE 1 illustrates the type rings which are to be dispensed.

FIGURE 2 illustrates a ring carrier upon which the rings of FIGURE 1 are positioned and aligned thereby.

FIGURE 3 is an isometric view of the device illustrating the dispenser and ring carrier in assembled form and includes the illustration of the location of the rings as they are about to be dispensed and picked up by a suitable applicator.

FIGURE 4 illustrates a dispenser in assembled form and is a side elevational view thereof.

FIGURE 5 is an isometric view of the cartridge loader of the dispenser in its unassembled form.

FIGURE 6 is an isometric view of the alignment bar of the dispenser in its unassembled form.

FIGURE 7 is an isometric view of the shim member of the dispenser in its unassembled form.

Referring to the drawing for more specific details of the invention, FIGURE 1 is an isometric view of the type clip ring 10 which is to be dispensed. This ring is formed having a substantially circular body 12 with an interrupted portion therein defining a pair of jaws 14 and 16.

FIGURE 2 of the drawing illustrates a plurality of rings 10 shown in FIGURE 1 disposed on a ring carrier 18. Each ring is placed on the carrier at an axial end portion thereof and is removable therefrom in the same

2

manner. The carrier is formed in a hollow tubular configuration whereby the radius of curvature of the outside diameter of the member is slightly less than the radius of curvature of the inside diameter of the rings. Thus, upon stacking of the rings, they are free to axially move along the length of the carrier. A pair of longitudinally extending ridges 20 and 22 are formed on the outer circumferential surface equally circumferentially spaced from a center ridge 24 formed thereon with these ridges all being parallel with one another and extending along the axial length of the carrier. The ridges 20 and 22 are circumferentially spaced from one another on the carrier a distance substantially equal to the arcuate distance between the ring jaws 14 and 16 on the inside diameter of the ring and accordingly limit the rotative movement of the rings about the carrier.

FIGURES 3-7 illustrate a dispenser device 26 and the individual elements thereof on which the rings are disposed in position for the dispensing operation. The dispenser 26 comprises a base 28 and an alignment bar 30 secured to the base by one or more fastening bolts or screws 32. The alignment bar 30 as illustrated in FIGURES 3, 4 and 6 is formed in an L-shaped configuration wherein a horizontal leg 34 thereof engages the base 28 and is suitably secured thereto. A vertical leg 36 of the alignment bar is substantially perpendicular to the base member and has a flat wall surface area 38 thereon interrupted by a key slot 40 extending along a section of the length of the leg. This slot is adaptable to receive the center ridge 24 of the ring carrier for slideable engagement therewith and has a base or stop 42 provided at the lower end of the slot, thus limiting downward axial movement of the carrier. The cross-sectional configuration of slot 40 is not critical and it is only required that enough clearance be provided to accommodate center ridge 24 of the ring carrier. A pair of vertically spaced openings 44 and 46 are formed in leg 36 and are arranged so as to be located axially beneath the key slot 40 and cooperate with structure hereinafter described in detail.

A cartridge loader 48 as illustrated in FIGURES 3, 4 and 5, is disposed on base 28 and has a pair of openings 50 and 52 therein shown in FIGURE 5. Openings 50 and 52 are spaced in a manner to coincide with openings 44 and 46 respectively of the alignment bar. A screw or bolt 54 is disposed through opening 44 and threaded into opening 50 of the cartridge loader and thus serves as a means to attach alignment bar 30 to the cartridge loader. An alignment pin 56 is disposed through opening 46 and is frictionally secured in opening 52 serving to align and position bar 30 with cartridge loader 48. Cartridge loader 48 has a base portion 58 in engagement with base 28 of the dispenser. A shoulder surface 60 is formed on loader base 58 and a pair of opposed slots 64 are formed in the cylindrical portion 62 at the intersection of that portion with shoulder 60. (The purpose thereof will be described later.)

In order to properly position cartridge loader 48 with respect to alignment bar 30, a surface 66 is provided parallel to the axis of the cylindrical portion 62 thus defining a longitudinal segment of a solid cylinder and further providing a recess to receive a shim member to be hereinafter described.

A mounting cylinder portion 70 is formed integral with cylindrical portion 62 and is of a smaller diameter than the arcuate portion 62; thus, a shoulder 68 is formed between mounting cylinder 70 and cylindrical portion 62. The diameter of mounting cylinder portion 70 is slightly less than the inside diameter of ring carrier 18 so that carrier 18 is readily receivable on the mounting cylinder. Shoulder surface 68 is of a thickness substantially equal

to the thickness of the carrier and accordingly, the carrier upon being placed on mounting cylinder 70, abuts this shoulder and is restrained from further downward axial movement thereon.

A shim member 72 as illustrated in FIGURES 3, 4 and 7 of the drawing, is disposed intermediate the alignment bar 30 and loader 48 and abuts surface 66 and wall surface 38 of leg 36. This shim is formed in a substantially rectangular solid configuration whereby surfaces 74 and 76 thereof are arranged so as to abut surface 66 of the loader and wall surface 38 of leg 36 respectively. A pair of openings 78 and 80 are also formed in the shim and are in alignment with the openings formed in the loader and in the bar while being similarly adaptable to receive the securing bolt 54 and alignment pin 56. The twofold function of the shim is to locate the loader with respect to the bar and accordingly, allow the center ridge 24 of the ring carrier access to the key slot 40 located on the alignment bar; also, when rings 10 slide from carrier 18 onto cylindrical portion 62 and are no longer in contact with the outside ridges 20 and 22 of the carrier, the shim is disposed in the open jaw of the rings and thus end surfaces 82 and 84 prevent relative rotation between the rings and the loader. The shim therefore serves in the relationship as a spacer and positioner and also as a means to insure proper orientation of the rings when transfer from carrier 18 to the dispenser is effected. It is important to note that the shim must be of a width less than the distance between the jaws 14 and 16 of the rings to be dispensed in order to maintain proper ring alignment.

At such time when the rings are ready for dispensing as disclosed in FIGURE 3, the lowermost ring of the stack rests on shoulder surface 60 of the loader. Slots 64 are formed in the lower cylindrical portion 62 of the loader and are spaced from one another at diametrically opposed positions a distance substantially equal to or less than the width of the shim member of the device. Since slots 64 are in coplanar relationship with the bottom ring, the ring jaws can be moved through the slots 40 and the ring removed from the loader in a direction perpendicular to the loader axis.

The rings are removed from the loader by a suitable applicator tool 86 which is illustrated in FIGURE 3 of the drawing. This applicator comprises a body and handle (not shown), and a pair of fingers 88 and 90 extending from the body. These fingers are laterally spaced and are capable of being resiliently biased from one another with the finger ends forming a pair of jaws 92 and 94. The jaws have arcuate recessed portions 96 and 98 formed therein with the configuration of the recess having a radius of curvature slightly less than the radius of curvature of the outside diameter of the ring. The jaws of the tool upon engagement with the ring which is to be dispensed, grip the axial outside diameter surface of the ring and through the resilient characteristic of the fingers, hold the ring tightly in the recess of the jaws as the ring is slipped past the slots 64 of the loader. Thus the ring is properly located in the applicator and is ready for placement in the desired location.

The dispenser as disclosed is operable to handle a particular size clip ring. A feature of this invention lies in the interchangeability of the elements of the dispenser to accommodate various sized rings. As an example, if a larger diameter ring were necessary and appropriate for a particular application, in the dispenser assembly, the shim and cartridge loader would be changed to accommodate the new ring size. The cartridge loader of the dispenser must correspond in dimension to the ring dimensions at the cylindrical portions thereof particularly as to the radius of curvature of the rings. Also the dimensions of the upper cylindrical portion of the loader which receives the ring carrier and the ring carrier itself must correspond to maintain operability of the device.

The shim dimensions therefor must be such that the

assembly of the ring carrier on the loader will be made in proper alignment through the utilization of the key slot located in the alignment bar. Further, the width thereof must be of a dimension slightly less than the linear distance between the ring jaws at the inside diameter of the ring. Because of the above recited simplicity in this structure and ease of assembly of the device, such a change can readily be made.

To more fully understand the new and novel features of the device, a typical operating cycle from the loading of the carrier to the dispensing of the rings will be described in detail as follows.

The rings 10 are manually or automatically placed on carrier 18 at one axial end thereof and are stacked to the desired number determined by the carrier length. The ring jaws slideably engage the carrier ridges 20 and 22 and are aligned thereby preventing rotative movement of the rings about the carrier. The carrier tubular configuration is designed to dimensionally coincide with the loader of the dispenser and upon assembly, the carrier slides over mounting cylinder 70 of the loader and one end thereof abuts the shoulder 68. Since this shoulder is of a width equal to the thickness of the carrier, the carrier is restrained from further downward movement on the loader while the rings are free to slide, gravitationally down the carrier and onto the loader cylindrical portion 62 without interference from the shoulder. The carrier is aligned on the loader by the introduction of the center ridge 24 thereof into the key slot 40 of the alignment bar. The rings therefore are aligned and thereby pass over the shoulder onto the loader.

The ring jaws, once leaving the contact and alignment of the carrier ridges, are maintained in the same alignment as initiated by the carrier ridges by shim surfaces 82 and 84. The slots 64 as formed in the cylindrical portion 62 are diametrically spaced so as to enable the jaws of the rings to slide from the shim surfaces 82 and 84 past the cylindrical portion 62 of the loader. The applicator accordingly is directed to the loader and picks up the rings at an angle perpendicular to the axis of the loader and thus the rings are dispensed and ready for application.

While this invention has been described in connection with certain specific embodiments, the principle involved is substantially capable of numerous other applications that would readily occur to persons skilled in the art. The invention, therefore, is limited only as indicated by the scope of the appended claims.

I claim:

1. A clip ring dispenser operable to position clip rings disposed thereon for transfer to an applicator, each of said rings being substantially annular in shape having a continuous annular surface thereon defining an inner diameter with an interrupted portion in said rings to define a pair of jaws, said dispenser comprising a base member, an aligning means secured to said base member, ring loading means disposed on said base member and positioned thereon by said aligning means, surfaces on said ring loading means for permitting removal of said rings therefrom, means located intermediate said aligning means and said ring loading means operable to laterally space said aligning and ring loading means on said base member, ring carrying means having rings thereon disposable on said ring loading means, said aligning means having a recess, structure on said ring carrying means for reception in said recess to maintain the ring carrying means fixed against rotation with said ring jaws engageable with said spacing means and being maintained in circumferential alignment with said surfaces on said ring loading means.

2. A clip ring dispenser operable to position clip rings disposed thereon for transfer to an applicator, each of said rings being substantially annular in shape having a continuous annular surface thereon defining an inner diameter with an interrupted portion in said rings to define a pair of jaws, said dispenser comprising a base member, an aligning means secured to said base member, a ring loading

means disposable on said base and positionable thereon by said aligning means, recessed surfaces on said ring loading means for permitting removal of said rings therefrom, ring carrying means having rings thereon disposable on said ring loading means and engageable with said aligning means, said aligning means including a recess, structure on said ring carrying means for reception in said recess to rotatably fix said ring carrying means on said ring loading means, a spacer intermediately disposed between said ring loading means and said aligning means, said rings being axially movable on said carrier and engageable with said spacer, said spacer being adaptable to fix said rings from rotation on said ring loading means for maintaining circumferential alignment of said ring jaws with said recessed surfaces on said ring loading means.

3. A clip ring dispenser operable to position clip rings disposed thereon for transfer to an applicator, each of said rings being substantially annular in shape having a continuous annular surface thereon defining an inner diameter with an interrupted portion in said rings to define a pair of jaws, said dispenser comprising a base member, an aligning means secured to said base member, a ring loading means positionable on said base by said aligning means, spacer means disposed intermediate said ring loading means and said aligning means, said ring loading means comprising a base portion formed on one end thereof engageable with said dispenser base, a first cylindrical portion disposed adjacent said base portion of said ring loading means, a first shoulder formed between said first cylindrical portion and said base portion, a second cylindrical portion disposed adjacent said first cylindrical portion, said second portion having a smaller diameter than said first portion forming a second shoulder therebetween, said first cylindrical portion having surfaces thereon defining a pair of slots disposed at the intersection of said first cylindrical portion with said first shoulder, ring carrying means disposable on said second cylindrical portion and engageable with said second shoulder, a surface on said aligning means, means on said ring carrying means cooperably engageable with said surface on said aligning means operable to fix said ring carrying means from rotation on said second cylindrical portion, said rings being axially movable on said carrier to said first cylindrical portion with said first cylindrical portion engageable with said ring inner diameter, said ring jaws being engageable with said spacer at the engagement of said rings with the base portion of said ring loading means and being maintained in circumferential alignment with said surfaces on said first cylindrical portion defining said slots for removal from said ring loading means.

4. A clip ring dispenser operable to position clip rings disposed thereon for transfer to an applicator, each of said rings being substantially annular in shape having a continuous annular surface thereon defining an inner diameter with an interrupted portion in said rings to define a pair of jaws, said dispenser comprising a base member, an alignment bar member secured thereto, a loader member disposed on said base adaptable to receive said rings, a spacer member disposed intermediate said loader and said bar operable to space said loader from said bar, said loader formed as a substantially cylindrical member having a base portion, a first and a second cylindrical portion thereon forming a shoulder between said cylindrical portions, a ring carrier positionable on said second portion being axially restrained by said shoulder and rotatably fixed on said loader by said alignment bar, said rings being moveable from said carrier to said first cylindrical portion and being held in alignment thereon by said spacer, said first portion having a radius of curvature slightly less than that of said rings, said first cylindrical portion defining a pair of slots juxtaposed said loader base, said slots defined by said first cylindrical portion being diametrically spaced from one another a distance less than the distance between said ring jaws and being of a width substantially equal

to the thickness of one of said rings, said slots defined by said first cylindrical portion being adapted to allow said rings to be removed from said first cylindrical portion of said loader in a direction substantially normal to the axis of said loader.

5. A clip ring dispenser operable to position clip rings thereon for transfer to an applicator, each of said rings being substantially annular in shape having a continuous annular surface thereon defining an inner diameter with an interrupted portion in said rings to define a pair of jaws, said dispenser comprising a base member, an alignment bar member secured thereto, a loader member disposed on said base adaptable to receive said rings, a shim member disposed intermediate said loader member and said bar member operable to laterally space said loader from said bar, said loader member formed in a substantially cylindrical configuration comprising a first and second portion having a shoulder formed therebetween and a base at the end of said first portion remote from said shoulder, a tubular ring carrier receivable on said second portion, said tubular ring carrier having a thickness being substantially equal to the width of said shoulder and being axially restrained from movement on said loader member thereby, a recessed surface formed on said alignment bar member, means on said carrier being cooperably engageable with said recessed surface on said alignment bar member operable to restrain rotatable movement of said carrier on said loader member with said shim operable to effect said cooperation and to align said rings on said loader member, said loader member being adapted to permit removal of said rings therefrom by said applicator.

6. A dispenser according to claim 5 wherein said tubular ring carrier comprises a wall portion and a series of radially extending circumferentially spaced ridges thereon, said ridges being axially directed throughout the length of said carrier, a pair of said ridges being operable to abut said ring jaws circumferentially aligning said rings on said carrier and preventing relative rotation therebetween, a further one of said ridges being operable to cooperate in sliding engagement with said recessed surface on said bar member effective to prevent relative rotation of said carrier on said loader.

7. A dispenser according to claim 6 wherein said series of ridges comprise a centrally located ridge and a pair of ridges equally spaced on each side of said centrally located ridge, said pair of ridges operable to rotatably restrict said rings from relative rotation therebetween, said bar ridge cooperable with said recessed surface on said bar member, preventing rotation of said carrier on said loader.

8. A clip ring dispenser operable to position clip rings disposed thereon for transfer to an applicator, each of said rings being substantially annular in shape having a continuous annular surface thereon defining an inner diameter with an interrupted portion in said rings to define a pair of jaws, said dispenser comprising a base member, an alignment bar member secured to said base member, a loader member disposed on said base adaptable to receive said rings, a shim member disposed intermediate said loader and said bar and being secured to said loader and bar members in lateral alignment therewith on said base, said loader formed in a substantially cylindrical configuration having a base portion, a first cylindrical portion, a second cylindrical portion, a shoulder formed between said first and second portion, a ring carrier engageable with said second portion and being receivable thereon, said carrier being axially restrained from movement on said loader by said shoulder, said carrier being cooperably engageable with said alignment bar with said engagement being operable to restrain rotatable movement of said carrier on said loader, said rings disposed on said carrier being slideable to said first portion of said loader with said first portion being engageable with said continuous annular surface thereof, said first portion defining

a recess therein adaptable to receive said shim with said recess defined by said first portion axially extending throughout the length of said first portion, one end of said shim being abuttable with said second portion of said loader at said shoulder, said shim width being slightly less than the distance between said ring jaws and being adaptable to engage said ring jaws preventing relative rotation therebetween on said first portion of said loader, said loader having portions thereon defining slots effective

5
8
to permit removal of said rings from said loader by said applicator.
